(57) **CLAIM**

The ornamental design for a vent for a soffit panel with short top holes, as shown and described.

DESCRIPTION

FIG. 1 is an isometric view of a vent for a soffit panel with short top holes according to an exemplary embodiment; FIG. 2 is a top plan view of the vent for a soffit panel with short top holes shown in FIG. 1;

FIG. 3 is a bottom plan view of the vent for a soffit panel with short top holes shown in FIG. 1;

FIG. 4 is a bottom-end elevation view of the vent for a soffit panel with short top holes shown in FIG. 2;

FIG. 5 is a top-end elevation view of the vent for a soffit panel with short top holes shown in FIG. 2;

FIG. 6 is a left-side elevation view of the vent for a soffit panel with short top holes shown in FIG. 2;

FIG. 7 is an enlarged detail of FIG. 6; and,

FIG. 8 is a right-side elevation view of the vent for a soffit panel with short top holes shown in FIG. 2.

Broken lines in the drawings indicate environmental structure of the vent for a soffit panel with short top holes that form no part of the claimed design.
